UNITED STATES PATENT OFFICE.

KURT W. E. HAMANN, OF TRUMBULL, CONNECTICUT

VAPOR CONDENSER FOR RADIATORS.

Application filed August 8, 1925. Serial No. 49,025.

This invention relates to condensing devices and pertains particularly to a condenser device adapted to be attached to the filling inlet of an automobile radiator.

5 The primary object of this invention is
the provision, in a manner as hereinafter set
forth, of a vapor condenser which when at-
tached to the radiator of an automobile, will
receive and condense the vapors generated in
10 the radiator and return the liquid to the ra-
diator thereby preventing the loss of the
same through evaporation. A device of this
type is particularly desirable during the
season when alcohol or other easily volatile
15 liquids are placed in the radiators with the
water to prevent the freezing of the same.
A slight rise in temperature of the liquid
causes the alcohol to be vaporized and unless
some device of this character is employed the
20 alcohol will be quickly dissipated. The de-
vice is also very efficient for summer use for
it obviates the necessity of having to con-
tinually refill the radiator when the liquid
therein is raised to a high degree of tem-
25 perature through long continuous driving
of the machine.

A further object of the invention is the provision, in a manner as hereinafter set forth, of a radiator attachment of the type described which will be of neat and attractive appearance making a very desirable ornament for the vehicle.

A still further object of the invention is the provision, in a manner as hereinafter set forth, of a condenser which will be of simple construction, strong and durable, and efficient for the purpose set forth.

The invention will be best understood from a consideration of the following detailed description taken in connection with the accompanying drawing forming a part of this specification, with the understanding that the invention is not confined to any strict conformity with the showing of the drawing but may be changed and modified so long as such changes and modifications mark no material departure from the salient features of the invention as expressed in the appended claims.

50 In the drawing:

Figure 1 is a longitudinal sectional view taken through the device embodying this invention, taken upon the line 1—1 of Figure 2.

53. Figure 2 is a section taken upon the line 9-9 of Figure 1.

Figure 3 is a section taken upon the line 3—3 of Figure 1 and,

Figure 4 is a section taken upon the line 4-4 of Figure 1.

The condenser device embodying this invention comprises a base or main body portion 1 of elongated tubular conformation and having the interior of the lower portion threaded as indicated at 2 and the upper portion of slightly increased diameter to set up the head 3 the interior of which head is threaded as indicated at 4. Formed within the body across the interior of the same at a point adjacent the lower portion of the head 1 is a wall or partition 5 which divides the body into an upper and lower chambered portion 6 and 7 respectively. 70 75

Within the lower portion 6, there is set up a smaller chamber or well 8 by the formation of the wall 9 within the portion, the upper part of which wall merges with the partition 5 and the lower portion with the bottom 10 while the side edges thereof merge with the wall of the body 1. Formed through the partition 5 is an inlet aperture 11 which opens into the well 8 and threaded into the bottom 10, is a plug 12 which closes a drain opening in the lower portion of the well. This plug 12 has a recess 13 formed in the end thereof which communicates with a downwardly extending passage 13^a formed through the bottom 1 and into this downwardly extending passage the end of a thumb screw 14 is extended to normally close the same. When the well 8 is to be emptied the thumb screw 14 is removed and the contents of the well allowed to flow therefrom through the passage 13^a into the lower portion 6.

Threaded into the lower end of the body 1 is a closure 15 which is provided with a centrally threaded aperture in which a nipple 16 is designed to be engaged.

When the device is to be secured to a radiator, the radiator cap, a small portion of which is indicated at 17, has a passage bored through the central portion thereof through which passage the nipple 16 is extended. A washer 18 is then positioned over the inner end of the nipple and a securing nut 19 threaded thereon and tightened against the washer 18 which in turn is formed against the underside of the cap 17 and acts to draw the body securely against the outer side of the cap. The device is thus secured in position upon the radiator cap and the cap may

be inserted or removed into or from the radiator as desired.

Coiled or wrapped about the outside of the body portion 1 beneath the head 3, is a condenser pipe or tube 20 formed preferably of copper tubing, and the lower end of this tubing is extended through the side wall of the body as indicated at 21 while the upper end enters the body at a point slightly beneath the partition 5 and extends upwardly and inwardly thereinto and through the partition as indicated at 22, opening into the upper portion 7 in the head 3.

Extending through the partition 5 is another tube, which tube is straight and relatively short as indicated at 23. The lower portion of the tube 23 extends a slight distance beneath the partition 5 into the portion 6 while the upper portion thereof extends a substantial distance above the partition 5 and above the top of the head 3.

Upon the upper portion of the body 1 there is mounted a condensing globe 24 which globe is preferably constructed of heavy glass. This globe as shown is hollow and has an opening formed therethrough from about the edge of which opening the exteriorly threaded collar 25 extends and this collar is threaded into the head 3 as is shown. The upper end 22 of the coil 20, the extended upper portion of the tube 23 and the passage 11 all open into this globe 24 as shown.

Formed at diametrically opposite points upon the head 3 of the body are two outwardly extending arms 26 and 27 respectively, the terminal outer ends of which arms are upturned as indicated at 28 and provided with interiorly threaded axial recesses 29, the lower portions of which recesses have opening thereto the ends of tubes 30 which are embedded in and extend throughout the length of their respective arms. The inner ends of these tubes extend through the partition 5 in the body and are bent as at 31 to curve downwardly into the well 8.

Threaded into the recesses 29 in the ends of the arms 26 and 27 are caps 32, hollow and having therein a plurality of transversely extending apertured partitions 33. The tops of these caps are provided with a series of openings 34 as shown. These caps together with the associated structure constitute a relief structure for the condenser device as will be described hereafter.

When the condenser device is fixed in position upon a radiator cap, after the usual over-flow tube provided for all radiators has been closed, and the contents of the radiator has reached the point of vaporization, the vapors will pass upwardly into the globe 24, through the tube 23 and also through the coiled tube 20. The vapors passing through the tube 20 will be mostly condensed before

reaching the globe 24 and the condensed liquid will then of course flow back through the outlet 21 of the tube and back into the radiator. The vapors passing through the tube 23 will enter the globe 24 and be condensed therein, the condensed liquid settling into the chamber 7 and flowing through the passage 11 into the well 8 and through the upper end of the tube 22 back through the coil into the radiator. The well 8 will of course become filled eventually and the liquid in this well will seal the ends of the tubes 30 against the escape of any vapor from the condenser device. In the event that the vapor is not condensed rapidly enough to prevent a strong pressure being exerted upon the interior of the globe 24, the pressure set up will be relieved by forcing some of the liquid from the well 8 through the tubes 30 into the cap 32 thus allowing the proper expansion of the vapor or the escape of some if necessary.

From the foregoing description it will be readily seen that there has been provided a vapor condenser of unique design, simple in construction, inexpensive to manufacture and easily and quickly applied as well as one which will be efficient for the purpose set forth.

Having thus described my invention what I claim is:—

1. A condenser device of the character set forth, comprising, a hollow body transversely partitioned to form an upper and a lower portion, means for securing said body in a position to receive vapor into said lower portion from an automobile radiator, means to set up a closed well within said lower portion having communication with said upper portion, a condenser globe overlying said upper portion, means for passing vapor from said lower portion into said globe, a pressure relief expansion means, and a tube connecting said relief means with said well.

2. A condenser device of the character set forth, comprising a hollow body transversely partitioned to form an upper and a lower portion, means for securing said body in a position to receive vapor into said lower portion from an automobile radiator, means to set up a closed well within said lower portion having communication with said upper portion, a condenser globe overlying said upper portion, means for passing vapor from said lower portion into said globe, a pressure relief fluid expansion means, a tube connecting said relief means with said well, and a condenser tube wrapped about said body and having one end opening into said lower portion and the other end opening into said globe.

3. A condenser device of the character set forth, comprising a hollow body transversely partitioned to form an upper and a lower portion, means for securing said body in a

position to receive vapor into said lower portion from an automobile radiator, means to set up a closed well within said lower portion having communication with said upper portion, a condenser globe overlying said upper portion, means to provide a chamber exteriorly of said body and opening to the

air, and a tube leading from said last mentioned chamber to said well to allow vapor from said globe to expand thereinto. 10

In testimony whereof, I affix my signature hereto.

KURT W. E. HAMANN.
